UNITED STATES PATENT OFFICE.

WILLIAM P. WOOD, OF ROSEBERRY, BRITISH COLUMBIA, CANADA.

LEVEL.

1,230,258.

Specification of Letters Patent. Patented June 19, 1917.

Application filed May 5, 1916. Serial No. 85,809.

To all whom it may concern:

Be it known that I, WILLIAM P. WOOD, a citizen of the United States, residing at Roseberry, in the Province of British Columbia and Dominion of Canada, have invented certain new and useful Improvements in Levels; and I do hereby declare the following to be a full, clear, and exact description of the invention, such as will enable others skilled in the art to which it appertains to make and use the same.

This invention relates to a level which may be used for ascertaining the pitch of rafters, for laying sewers, water pipes or building flumes, or for any other purpose for which an ordinary level is employed.

The primary object of the invention is to provide a level which is comparatively simple in construction, and includes a body and a rotatable weighted disk carried by the body and having peripheral graduations formed upon its periphery and about its circumference for coaction with an indicating finger carried by the body and further to provide a brake structure for retarding the rotation of the weighted disk.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:

Figure 1 is a side elevation of an improved level showing parts thereof broken away,

Fig. 2 is a top plan view of the level having parts of the body broken away,

Fig. 3 is a section on the line 3—3 of Fig. 1; and

Fig. 4 is a section on the line 4—4 of Fig. 1.

Referring more particularly to the drawings, 1 designates the body of the level, which may be constructed of wood, or any suitable material, such as is ordinarily employed in the construction of bodies of various types of levels.

The body 1 of the level is provided with a recess 2 formed therein centrally of its ends. Metallic plates 3 are secured to the

body 1 and form closures for the lower half of the recess 2. The upper half of the recess 2 is inclosed by transparent panes 4 which permit the exhibiting of the interior of the upper portion of the opening 2. Glass or transparent panes 4 are properly held in place by any suitable means. The top of the body 1 is provided with a rectangular opening 5, which has a transparent pane 6 mounted therein to permit of the viewing of the interior of the compartment 2 from the top.

A pin 7 is rotatably supported by the metallic plate 3 and has suitable spacing collars 8 mounted thereon, which hold the disk 9 in its proper position upon the pin 7 and prevent movement of the disk longitudinally of the pin. The disk 9 is constructed of any suitable material and it has its upper half hollow as is clearly shown at 10 and its lower half solid, as is shown at 11, for providing a weighted bob or rotatable disk.

The upper hollow half 10 of the disk 9 is provided with graduations, 12 which are formed about the periphery of the same or on the side of the disk, as clearly shown in Fig. 1, and also with graduations 13 which are formed upon the rim or periphery of the disk, as clearly shown in Fig. 2. The graduations 13 are visible through the openings 5 in the transparent pane 6, while the graduations 12 are visible through the transparent panes 4. The graduations 12 and 13 are provided with a major graduation 12^a, 90 which is designated by zero and always remains perpendicular to the horizontal, and the axis of the disk, owing to the weighting of the lower half 11 of the disk. An indicating finger 14 is carried centrally by 95 the top of the body 1 and is positioned for alinement with the major graduation 12^a for indicating that the surface upon which the level is placed is perfectly level or horizontal. As the surface upon which the level 100 is placed is inclined, the disk, will, owing to the weighting of the lower half 11, remain so that the major graduation 12 will be perpendicular to the horizontal plane, and the degree or angle of the incline may 105 be determined by the graduation which aligns with the indicating finger 14.

A flat spring 15 is carried by the body 1 and has one end engaging one side of the lower weighted half 11 of the disk 9. A pin 110

16 is slidably inserted through one of the plates 3 and has its inner enlarged end engaging the spring 15 for forcing the spring forwardly into frictional engagement with 5 one surface of the disk 9 for retarding the movement of the disk and causing it to come to a rest after the entire level has been moved.

10 In reducing the invention to practice, certain minor features of construction, combination and arrangement of parts may necessitate alterations to which the patentee is entitled provided such alterations are comprehended within the scope of what is 15 claimed.

What is claimed is:—

1. In a level structure, the combination, of 20 a body provided with a centrally disposed recess, side plates forming closures for substantially one-half of said recess, a pin supported by said side plates, a disk rotatably mounted upon said pin and having its upper half hollow and its lower half solid, and 25 graduations formed upon each side of said disk about the periphery thereof, and an indicating finger carried by said body and adapted for coaction with said graduations, and means carried by said body for engagement with one side of said disk for arresting 30 movement of the disk.

2. In a level structure, the combination, of 25 a body provided with a central opening, side plates forming closures for portions of said openings, a pin carried by said side plates and extending through the openings, a disk rotatably mounted upon said pin, said disk having its upper half section hollow and its lower half section solid for 30 weighting the disk, graduations formed

upon the sides of said disk about the periphery of the same, graduations formed upon the periphery of said disk, an indicating finger carried by said body for coaction with said graduations, and transparent panes forming closures for the upper section of said opening, said body being provided with an opening positioned directly above the uppermost portion of said disk.

3. In a level structure, the combination, of 40 a body provided with a central opening, side 50 plates forming closures for portions of said openings, a pin carried by said side plates and extending through the openings, a disk rotatably mounted upon said pin, said disk having its upper half section hollow and its 55 lower half section solid for weighting the disk, graduations formed upon the sides of said disk about the periphery of the same, graduations formed upon the periphery of said disk, an indicating finger carried by 60 said body for coaction with said graduations, and transparent panes forming closures for the upper section of said opening, said body being provided with an opening positioned directly above the uppermost 65 portion of said disk, a flat spring carried by said body and engaging one side of said disk, and a pin slidably carried by said body and engaging said spring for moving 70 said spring into frictional engagement with said disk for retarding movement of the disk.

In testimony whereof I affix my signature in presence of two witnesses.

WILLIAM P. WOOD.
